United States Patent Office

Des. 195,005
Patented Apr. 9, 1963

195,005

CONTAINER FOR DAIRY PRODUCTS OR THE LIKE

Clara Virginia Eicholtz, Midland, Mich., assignor to The Dow Chemical Company, Midland, Mich., a corporation of Delaware

Filed Nov. 17, 1961, Ser. No. 67,569

Term of patent 14 years

(Cl. D58—17)

FIGURE 1 is an elevational view of a container for dairy products or the like showing my new design;

The side of the container not shown is the same as that illustrated.

I claim:

The ornamental design for a container for dairy products or the like, as shown and described.
